UNITED STATES PATENT OFFICE.

WILLIAM COLIN RUSSELL, OF EAST SHEEN, ENGLAND.

AIRSCREW HAVING ADJUSTABLE BLADES.

1,389,991.

Specification of Letters Patent. Patented Sept. 6, 1921.

Application filed May 15, 1920. Serial No. 381,675.

To all whom it may concern:

Be it known that WILLIAM COLIN RUSSELL, a subject of the King of Great Britain, residing at 63 Palewell Park, East 5 Sheen, county of Surrey, England, has invented certain new and useful Improvements in and Relating to Airscrews Having Adjustable Blades, of which the following is a specification, reference being had therein 10 to the accompanying drawing.

This invention relates to propellers or airscrews for aircraft whereof the blades are adjustable about their longitudinal axis and has for its object to effect certain improvements which while being particularly applicable for use with propellers or airscrews of the kind forming the subject of my application for Letters Patent Ser. No. 345300 are also adapted for employment with airscrews generally where the blades are adjustable in the manner above referred to.

The present invention consists essentially in the provision of improved means for controlling and operating the adjustment of the 25 blades and for indicating the extent to which the blades are adjusted at any moment during flight.

In connection with airscrews such as described in my aforesaid prior patent application and others the mechanism for adjusting the blades is designed for actuation by rotary motion and is mounted so as to revolve with the airscrew it being necessary to impart the said actuating rotary motion from 35 a non-revolving part of the engine or aircraft.

Various methods have been proposed or adopted for accomplishing this operation, for instance a gear wheel mounted concentrically with the air screw shaft and meshing with a similar wheel in connection with the blade adjusting mechanism the said concentric wheel being adapted to normally rotate with the shaft, but also to be restrained 45 or held stationary by means of a band brake, the gear wheel of the adjusting mechanism being thereby caused to roll around it and revolve the said mechanism. Another instance is that in which reverse motion is obtained by mounting concentric gear wheels on sleeves one upon the other and geared to the blade adjusting mechanism so that when held by their respective band brakes the one 50 imparts forward motion and the other reverse motion to the blade adjusting mecha-

nism. These means of control are normally out of continuous positive connection with the blade setting mechanism and afford no guide to the blade setting at any given moment.

The present invention is designed to provide means for effecting the control by a continuous positive connection with the blade adjusting mechanism in conjunction with an indicator adapted to show the exact setting of the blades at any moment, the means of control being simple in character and convenient either for direct operation by hand or automatically.

With these ends in view the device of the present invention comprises a blade control gear box mounted conveniently upon a non-rotating framework, the function of which is to cause a gear wheel or the like mounted concentrically with the airscrew shaft and arranged in positive connection with the blade setting mechanism to rotate normally at the same speed as the airscrew shaft so that no drive is imparted to the blade setting mechanism, the mechanism within the box being capable of operating so as to accelerate or reduce the speed of revolution of said concentric gear wheel by a definite and known amount resulting in corresponding proportional adjustment of the airscrew blades and indicator.

In order that the invention may be readily understood and carried into effect the same will now be more particularly described with reference to the accompanying drawings in which:—

Figure 1 is a view in section showing an adjustable airscrew mounting in accordance with my aforesaid previous application and having the present improvements applied thereto.

Fig. 2 is a section through the T-shaped headpiece or yoke termination of the airscrew shaft showing a means of mounting the chain wheels.

Fig. 3 is a transverse section through the head piece or yoke and pivots showing an alternative arrangement of chain wheel drive.

Fig. 4 illustrates another arrangement in which the concentric gear wheel is carried by a sleeve mounted freely upon the airscrew shaft the operating shaft being disposed remote from the airscrew shaft.

Fig. 5 is a diagrammatic view illustrating

a form of balanced or differential gear for use in effecting the control of the setting mechanism.

Fig. 6 shows a general arrangement of the frame and gear box and gearing.

- Although for convenience of explanation I have shown certain details of the adjustable airscrew described in my aforesaid former application for Letters Patent Serial 10 No. 345300 with my present improvements applied thereto I do not limit the application thereof to such construction or details now, it should be noted in connection with the type of adjustable airscrew illustrated, that 15 the blade adjusting mechanism being irreversible any gearing operating it will be running "light" except when effecting a resetting of the blades. Further it is not sought to claim as an original feature by itself a hollow airscrew shaft as a means of mounting the operating shaft of a blade adjusting device or a sleeve upon and concentric with the airscrew shaft as a means of mounting an annular gear wheel.
- 20 Referring to Fig. 1 of the drawings the airscrew shaft A terminates in a tubular T-shaped headpiece or yoke A¹ in which the adjustable blade pivots B and C are mounted the outer pivot B being provided with an end plate B¹ for the attachment of the butt of the blade (not shown) and the inner pivot C with an end plate C¹ for a similar purpose. The rotary adjusting movement of the pivots is effected by means of the drum 25 D whereof the helical groove D¹ actuates the levers B^x and C^x formed or provided on the respective pivots B and C or the end plates B¹, C¹ respectively pertaining thereto. The levers B^x and C^x respectively terminate in 30 pins or studs B²¹ and C²¹ which engage in the said groove D¹ and the drum is supported upon an axle D² carrying a worm wheel D⁴ which may be rotated by the worm E¹ on the shaft E. It will be seen that upon 35 the worm wheel D⁴ being operated by the worm E¹ the rotation of the drum D will be effected and the engagement of the pins or studs in the helical groove D¹ deflecting the levers B^x and C^x and consequently turning 40 the pivots B and C about their axes. The shaft E extends rearward to a point adjacent to the airscrew shaft terminal. According to the improved arrangement in which a concentric gear wheel is in positive connection and drive with the said shaft E the airscrew shaft A is formed with a hollow interior for the reception or passage of a shaft H the tubular head piece A¹ being formed with a recess A⁴ to receive the chain 45 50 55 60 65 70 75 80 85 90 95 100 105 110 115 120 125
- wheel H¹ mounted upon the end of the shaft H. This shaft H is mounted in suitable bearings (not shown) so as to be capable of rotating freely. The chain wheel H¹ is connected by a chain H^x (Fig. 2) to a chain wheel E³ fixed upon the shaft E. As will

be seen on reference to the drawings particularly Fig. 2, the said chain H^x passes and works through slots provided by cutting away portions of tubular head piece A¹. Other forms of positive gearing or the like 70 may be employed for operatively connecting the shaft H to the shaft E so as to actuate the drum D or other device for effecting the setting or adjusting of the blades.

According to the alternative arrangement 75 illustrated in Fig. 3 the shaft H is passed directly through the hollow airscrew shaft A head piece A¹ and pivots B and C the chain wheel H¹ being attached to the protruding end of the said shaft H and the connection with the blade setting mechanism being made at the front of the head piece A¹. In order to provide for the rotation of the pivots B and C about their axes radial openings or slots B³ and C³ respectively are 80 85 formed therein for the passage of the shaft H.

In another alternative arrangement shown in Fig. 4 a sleeve S is mounted on the airscrew shaft A a concentric gear wheel S¹ 90 being formed with or attached thereto. The sleeve S is freely mounted on the said shaft A and also carries therewith or has secured thereto a chain wheel S² the latter being connected by a chain S^x with a chain wheel 95 H¹ on the driving shaft H mounted in bearings on a non-revolving framework. The concentric spur wheel S¹ meshes with a spur wheel E⁴ on the shaft E which carries the worm E¹ for operating the worm wheel D⁴ 100 pertaining to the drum D of the blade setting or adjusting device. Any form of positive gearing or the like may be used to transmit the drive from the shaft H to the shaft E via the sleeve S, the said shafts A and H 105 being each connected positively to the controlling gear box by any convenient form of gearing. In Fig. 6 I have illustrated one form but I do not limit myself to any particular means of positively connecting them 110 through the gear box or to any particular place for mounting the said gear box.

For controlling the rotation of the concentric gear wheel (or any equivalent gearing providing positive connection with the blade setting or adjusting mechanism an epicyclic differential or balanced driving gear is provided similar in principle to the type commonly employed in the driving axles of motor vehicles whereby a main driving member transmits balanced drive to two shafts or wheels with freedom for the one shaft or wheel to over-run the other while both retain positive driving connection with the main driving member.

The component parts of such a gear applied in the present invention will be more clearly understood by reference to the diagrammatic view Fig. 5 wherein an axle N has freely mounted thereon a bevel planet

wheel cage P having pins P^1 on which bevel planet wheels P^2 are mounted with freedom to rotate and which latter mesh on either side with "sun" bevel wheels S^3 and R also 5 freely mounted on the shaft N. If the cage P be rotated at a constant speed and one wheel (R for instance) be held stationary the other wheel (S^3) is caused to rotate twice as fast as P and in the same direction 10 and if the wheel R be also rotated it tends to turn the felly wheel S^3 in the opposite direction so causing the rotation of the latter wheel to be either accelerated or retarded according to whether the rotation of R acts 15 with or against the motion imparted by P. Thus the normally stationary sun wheel R can act when rotated as a speed regulator in the transmission of drive from P to S^3 causing the latter to gain or lose a definite 20 member of turns in relation to P equal to the member of turns given to R. According to an alternative arrangement of the same component parts the wheel R may be the driving member the cage P the regulator 25 normally held stationary and the wheel S^3 the driven member. Rotation of P then causes the driven wheel S^3 to gain or lose in relation to the driving wheel R two turns for every turn of the cage P. 30 Various re-arrangements of the same component parts may be made to meet the requirement of a driving member, a driven member and a regulator member normally held stationary and I do not limit myself to 35 any particular arrangement of the said gear nor do I limit myself to any particular type of differential or balanced drive gear, such as the bevel type illustrated, as any of the types designed for use on vehicles or the 40 like may obviously be adapted to the invention provided the same function is performed or fulfilled.

In the application of the differential gearing above described to air screw blade adjustment the driving member is caused to revolve at a speed proportionate to and in keeping with that of the airscrew shaft and transmits motion through the "driven member" to the concentric gear wheel connected 45 to the blade adjusting mechanism so that the said gear wheel rotates normally as one with the airscrew shaft but by the rotation of the "regulator" member of the differential gear it may be caused to make a definite 50 number of turns more or less than the airscrew shaft with a proportionate adjustment of the airscrew blades. By suitably connecting the regulator member with an indicator a registering or indicating of the exact blade 55 setting at any movement may be obtained. 60

Referring now to Fig. 6 which illustrates one form of the gearing and its construction in combination with means of mounting the concentric gear wheel in its application to

65 control in connection with this invention, the

hollow airscrew shaft A and the central shaft H terminate within the gear box or frame K the said shafts being mounted in suitable bearings adapted to facilitate their rotation. The shaft N is also mounted freely in the 70 gear box or frame K and has fixed thereto the regulator sun wheel R while freely mounted thereon is the planet wheel cage or driving member P carrying the pins P^1 for the reception of the freely mounted 75 bevel planet wheels P^2 which mesh on the one side with the fixed wheel R and on the other with the driven wheel S^3 also mounted freely on the shaft N. One end of the shaft N is furnished with the operating handle M 80 whereby the wheel R may be rotated. The cage P carries a gear wheel P^3 which meshes with and revolves at half the speed of the gear wheel A^5 on the shaft A. The driven wheel S^3 carries a gear wheel S^4 which 85 meshes with a gear wheel H^2 of equal size on the shaft H. The shaft N at the end remote from the operating handle M is fitted with a worm N^1 which is adapted to drive the worm wheel T and the indicator hand 90 or pointer T¹ operatively connected therewith the said pointer traversing the scale T² so as to show the actual blade setting effected.

In the operation of the apparatus the handle M is normally locked or stationary. Thus the shaft A through spur wheel A^5 drives the cage P by means of the spur wheel P^3 at half its own speed and in the opposite direction and by the bevel wheels 100 P^2 rolling around the fixed sun wheel or "regulator" R also drives the "driven" wheel S^3 at twice its own speed and in the same direction i. e. at the same speed as, but in the opposite direction to, the shaft A. The 105 wheel S^3 through the spur wheel S^4 drives the spur wheel H^2 (of equal size) on the shaft H at its own speed in the same direction as shaft A. The shafts A and H therefore rotate as one including the concentric 110 gear wheel H^1 (Fig. 1), which is attached to the extremity of the said shaft H remote from the box K. Upon imparting a turning movement to the handle M the fixed "regulator" wheel R is caused to rotate thereby 115 increasing or decreasing (according to the direction of movement) the extent to which the wheels P^2 must roll in traveling around it and varying by a similar amount the drive imparted by them to the wheel S^3 resulting 120 in relative motion between the shafts A and H and the operation of the blade adjusting mechanism accordingly the pointer T¹ indicating or recording the exact amount of adjustment. The pointer T¹ may have the 125 speed ratio of its driving gear proportioned to give any convenient indication of airscrew blade adjustment.

A similar arrangement of differential gearing may be combined with the means 130

of mounting the concentric gear wheel illustrated in Fig. 4 the whole if desired being placed immediately behind the airscrew and constructed in one mechanism.

5 I do not limit myself to any particular place for mounting the said controlling gear box nor do I limit myself to any specific form of gearing for conveying motion for driving it or for connecting it to the concentric gear wheel.

10 The control shaft N may be adapted for operation by power instead of by hand and automatic control by means of a speed governor may be conveniently applied.

15 What I claim is:—

1. In means for propelling aircraft, the combination with the propeller shaft of rotative means concentric with said shaft, mechanism in positive connection with said 20 means for varying the angular adjustment of the propeller blades, and means on the aircraft for transmitting motion to said concentric rotative means comprising a main driving member adapted to normally transmit balanced drive to a pair of driven members which have the capacity of over-running one another, a member adapted to be held 25 stationary and mounted on the same axis as the driven members and through the said 30 driven member adapted to drive the concentric rotative means, and means for rotating said stationary member to accelerate or retard the movement of said rotative concentric means and thereby proportionally operate the blade setting and adjusting mechanism and effect the setting and adjustment of the propeller blades.

2. In means for propelling aircraft the combination with the propeller shaft of rotative means concentric with said shaft and in positive driving connection with mechanism for varying the angular adjustment of the propeller blades, and means on the aircraft for transmitting motion to said concentric rotative means, comprising a balanced drive gear embodying a central or epicyclic member adapted to transmit balanced drive to a pair of driven members which have the capacity of over running one 45 another, the drive to the said concentric rotative means being transmitted through the one member of balanced gear to the second by holding stationary the third, and means for rotating said stationary member to accelerate or retard the normal motion of the concentric means to proportionally operate the blade setting and adjusting mechanism and effect the setting and adjustment of the propeller blades.

60 3. In means for propelling aircraft the

combination with the propeller shaft of rotative means concentric with said shaft and in positive driving connection with blade setting and adjusting mechanism, means for transmitting motion to said concentric rotative means, comprising a balanced drive gear embodying a central or epicyclic member adapted to transmit balanced drive to a pair of driven members which have the capacity of over running one another, the drive to 65 the said concentric rotative means being transmitted through the one member of the balanced gear to the second by holding stationary the third, means for rotating said stationary member to accelerate or retard the 70 normal motion of the concentric means, and an indicating device geared to the said normally stationary member and adapted to indicate the amount of motion imparted to the blade adjusting mechanism and the setting 75 of the blades.

4. In means for propelling aircraft the combination with a hollow propeller shaft of a concentrically mounted inner shaft adapted to operate blade setting and adjusting 85 mechanism comprising a helically grooved drum and levers in operative relation therewith and a differential or balanced drive gear adapted to accelerate or retard the said inner shaft above or below the normal propeller shaft speed for the purpose of effecting blade adjustment.

5. In means for propelling aircraft, the combination with the propeller shaft, of rotative means concentric with said shaft, 95 mechanism in positive driving connection with said means for varying the angular adjustment of the propeller blades, and means on the aircraft for transmitting motion to said concentric means comprising a pair of 100 driven members which have the capacity of over running one another, a main driving member adapted to normally transmit balanced drive to said pair of driven members, a member adapted to be held stationary and 105 mounted on the same axis as the driven member and, through the said members, to drive the rotative concentric means, means adapted to rotate said stationary member to accelerate or retard the movement of said rotative concentric means, and an indicating device operated by the means for rotating the stationary member whereby the proportional 110 operation of the setting and adjusting of the propeller blades is effected and indicated.

W. COLIN RUSSELL.
